UNITED STATES PATENT OFFICE.

CARL L. BECKER, OF MARIETTA, OHIO.

ATTACHMENT FOR ADDING-MACHINES.

No. 892,116.

Specification of Letters Patent.

Patented June 30, 1908.

Application filed May 23, 1907. Serial No. 375,380.

To all whom it may concern:

Be it known that I, CARL L. BECKER, a citizen of the United States, residing at Marietta, in the county of Washington and State of Ohio, have invented certain new and useful Improvements in Attachments for Adding-Machines, of which the following is a specification, reference being had therein to the accompanying drawing.

10 My invention relates to adding machines and especially to that type of adding machines which use a printing lever for bringing the digit wheels into recording position and for printing the total on the recording tape. 15 Heretofore these printing levers have been operated by hand, and where the operator had to use one hand for turning checks or other papers and the other hand for pressing the digit buttons, it was very inconvenient to 20 operate the printing lever and necessarily caused considerable loss of time in a day's work. It is the object of my invention to obviate these difficulties and to provide a 25 simple and inexpensive device which may be removably secured to the printing lever and supporting frame of any standard machine, whereby both hands may be used in turning papers and in punching the buttons and the printing lever may be operated without loss 30 of time.

Briefly stated, the invention consists in providing a detachable bell crank lever which may be removably secured upon the shaft of and to the printing lever and which may be 35 controlled by a foot lever pivoted removably on the frame.

My invention is illustrated in the accompanying drawings, in which—

Figure 1 is a side elevation of a supporting stand with an adding machine mounted thereon and my attachment applied thereto, and, Fig. 2 is a detail perspective of the bell crank lever and its operating rod.

Referring to the drawings, 1 represents an adding machine which, in this instance, is seated upon a base 2 carried on the usual supporting frame which comprises legs 3 connected together by crossing tie bars 4. The adding machine is shown to be of the usual 45 Burroughs type with its printing shaft 5 projecting out from the side thereof and having secured to it the printing lever 6. The frame comprising the legs 3 and the tie rods 4 is of the common type and is provided with a 50 projecting stud 7 upon which is pivoted the foot lever 8 in this instance slotted at 9, so as

to removably engage the pivot post. This lever extends outwardly toward the front of the machine and is provided at its forward end with a foot piece 10 by which it may be 60 operated. Intermediate the pivot stud 7 and the foot piece 10, and nearly adjacent the latter, the lever 8 is provided with an aperture through which the lower hooked end of a connecting link 11 is passed, the upper end 65 thereof being secured to a laterally projecting lug 12 on the bell crank lever 13 in a similar manner. This bell crank lever 13 comprises a triangular piece of sheet metal stamped out as a whole from a single sheet of 70 material and having one of its corners bent into an apertured lug 12 to receive the hooked end of the connecting link 11. Upon the side opposite from the lug 11 two projecting ears 14 and 15 are bent over so as 75 to engage the printing lever 6 and below these ears the bell crank lever is notched or perforated at 16 so as to engage the shaft 5. The printing levers of all of these machines are returned to normal by a spring within the 80 casing (not shown) and the illustration indicates the operating device in normal position with the lever retracted. When it is desired to throw the lever to its forward position to accomplish the function of that member it is 85 only necessary to depress the lever 8 by pressure upon the foot piece 10 and thereby, through the connecting link 11, operating the bell crank lever to revolve the printing shaft. 90

I have shown the connecting link between the bell crank lever 13 and the foot lever 8 as a single integral rod with hooked ends to engage the hole in the foot lever 8 and the aperture in the lug 12 of the bell crank lever 13, 95 but in practice I preferably use a two part rod joined together by a turn-buckle by which the length of the rod may be adjusted. This enables me to secure the proper throw or length of travel for the printing lever. 100

In the ordinary supporting frame there is no stud 7 upon which to pivot the foot lever. I therefore pivot this lever directly upon the connecting bar which runs between the lower end of the legs. 105

From the foregoing description it is thought that the operation need not be further described and that it will be well understood by those versed in the art. It will also be seen that while I have described and illustrated a specific and simple form with which to accomplish a certain result I am not in any 110

way limited to the disclosure made as many changes might be resorted to and many modifications adopted without departing from the spirit or scope of the invention. I contemplate all such changes and modifications as within the purview of the appended claims.

Having thus described my invention what I claim and desire to secure by Letters Patent is

10. In a device of the class described, a supporting frame, a tie rod thereon, an adding machine mounted on said support, a shaft projecting therefrom, a handle on said shaft at right angles thereto, a rigid foot lever having an opening to engage said tie rod at the rear of the frame, and a projecting front end, a triangular member punched from sheet metal bent over at one point and perforated for the reception of the connecting rod, provided with a semi-circular bearing at its apex

adapted to fit upon this shaft, and provided with a pair of projections or lugs on the edge opposite the bent-over point, said lugs being returned upon themselves so as to form hooks to engage the aforesaid handle, and a rigid metal tie rod passing through a transverse opening in the foot lever at its lower end, at its upper end provided with a hook engaging an opening in the bent-over point of the triangular member, all of said parts forming a 30 unitary whole adapted for instant and ready removal to and from the adding machine without the aid of tools, substantially as described.

In testimony whereof I affix my signature 35 in presence of two witnesses.

CARL L. BECKER.
